HOOK RULE

Chester Paul Ashel, Appleton, Wis., assignor to
The L. S. Starrett Company, Athol, Mass., a
corporation of Massachusetts

Application June 1, 1939, Serial No. 276,787

7 Claims. (Cl. 33—173)

Hook rules and like devices of the mechanic's kit are of various types and have been made variously adjustable, but except for special jobs the usual mechanic has only one and in some small 5 shops there is no hook rule available.

My present concept includes certain improvements in hook rules as such, as well as novel attachments or accessories for other instruments or tools to provide the same with a hook rule 10 function.

While my present inventions are applicable to a variety of devices I have selected for the purposes of illustration a novel attachment which is a new accessory of varied utility and usable 15 with straight edges of measuring or other tools or with parts, such as the blades of adjustable squares and like tools.

The illustrative form shown in the accompanying drawing is a practical attachment well adapted for convenient use and for commercial production, which is suggestive of other modifications of form and use which will readily occur to those skilled in this trade.

In the drawing, in which parts are identified by 25 usual conventional reference characters,

Fig. 1 illustrates a clamping attachment in accordance with my invention, applied as a hook rule to the blade of an adjustable square.

Fig. 2 is a sectional view of the block of such 30 attachment with a fragment of a longitudinally grooved blade lodged in its channel and with hook pin in place but with clamp screw removed.

Fig. 3 is a view also in section of the block in reversed position showing both the hook pin and clamp screw but without any blade.

Fig. 4 is a transverse sectional view longitudinally through the block with pin hook and clamp screw removed.

Fig. 5 is a view transversely of the block in 40 partial section and showing a clamp screw and nut in place in relation to a blade taken on a general line indicated at 5—5, of Fig. 1, and

Fig. 6 is a plan view of such a rule block 45 illustrated as on a blade but viewed from its lower side.

My novel hook rule attachment is adapted to be used with any straight edged blade but more particularly a blade channelled on one side face between its edges. As in Fig. 1, I preferably 50 provide it as a block 1 and this, in the form shown, is preferably an oblong block slightly longer than its depth and having one corner on its outer end beveled as at 2 substantially to the line of the pin bearing so as to expose the pin at 55 this corner of the block. The block 1 is lon-

gitudinally channelled as at 3 to receive a straight edge or blade of any form or type of construction adapted to its width, as indicated in Figs. 1, 2 and 5.

Adjacent what may be considered as its inner end, regarded with reference to the head H of the adjustable square indicated in Fig. 1, I form a clamp screw receiving aperture 4 which is circular at its upper end where it passes through the upper part of the block 1 above the upper 10 wall or edge contacting surface 5 of the channel 3. This portion of the clamp aperture is transversely tapped as at 6 for receiving a retaining screw 7 (Fig. 5).

Below its upper end the clamp aperture 4 as 15 it intersects the blade receiving channel 3 preferably forms at one side a half cylindrical groove 8 in which can be lodged a half round stem of a threaded blade clamp 9 having its face flattened off as at 10 so as to bear against a blade such as 20 B having a usual clamping groove b between its opposite straight edges. At its lower end the half round threaded clamp piece 9 is formed with a foot 11 adapted to fit within the groove b. Above the half round portion of the threaded 25 clamp piece 9 it is formed of the full diameter of the wire of the stock and threaded as at 9' to receive a nut 12 for tightening the foot 11 against the upper edge of the groove b (Fig. 5).

At what we may consider as its outer end as 30 viewed in Fig. 1, i. e. away from the head H of the square of which the blade B may happen to be part as a tool commonly in machinists' boxes, I provide an aperture 13 to receive the pin 14 which serves as the hook. This aperture passes transversely through the upper part of the block 1 on what is really its solid back opposite to its open channel 3 and continues as opposite grooves 13', 13² in the side walls of the channel 3.

Referring to Fig. 4 it will be noted that the 35 channel 3 preferably divides the block 4 unsymmetrically so that one wall is more deeply grooved as at 13' than the other at 13². The unsymmetrical channel 3 also makes unsymmetrical the formation of the semi-cylindrical groove 8 for the half round screw portion 9 with a block of minimum thickness.

The hook pin 14 is preferably a cylindrical pin of uniform diameter throughout, but it is engaged frictionally progressively towards the lower edge 1' of the block. Preferably, below the upper portion 13 in which the pin 14 has an easy fit for entry, the opposite pin receiving grooves 13' and 13² are given a reduced diameter as by taper drilling or like expedient to obtain the de- 55

sired frictional fit with a maximum at the lower edge l' which comes adjacent the median line of the blade B when so mounted.

The hook pin 14 is preferably larger in diameter than the thickness of the usual blade on which such an attachment is intended to be used. This gives a maximum clamping surface or end bearing for the blade even though the blade may be actually somewhat off the vertical axial center of the pin due to the difference in thickness of the walls of the block l as before explained.

The hook pin 14 is normally set out as indicated in Fig. 2 when the device is used as a hook rule. If it be desired to use the attachment with an adjustable square, as suggested in Fig. 1, the pin 14 may be pushed down to a greater extent as may be desired and the head or like member 4 of the square or other instrument having a face h may be moved so that a piece of work placed between the hook pin 14 and the face h may be roughly calipered.

Various other uses as well as modifications in form will be readily suggested to those skilled in the art by my illustrative embodiment of my invention as shown in the drawing and as discussed in my foregoing specification and as hereafter claimed.

What I therefore claim and desire to secure by Letters Patent is:

30. 1. A hook rule attachment for the blade of an adjustable square or like device having an engageable clamping groove between its longitudinal edges, said attachment including a block channeled to provide a longitudinal blade bearing, 35 said block having a vertical clamp receiving aperture through its top, the inner face of said blade bearing channel being vertically grooved in axial alinement with said aperture, a threaded clamp screw in said aperture having a flattened portion extending into said vertical groove to provide a side bearing for said blade and having a foot at its lower end adapted to enter the groove in the blade, a nut on the screw for tightening the clamp foot in said blade groove, a pin receiving aperture in said block adjacent an outer end thereof and extending through the longitudinal blade bearing channel, and a cylindrical hook pin in said aperture of greater length than the vertical depth of said blade bearing, said pin being 40 of greater diameter than the thickness of the blade and being adjustably clamped against the end of the blade as said blade is clamped in its bearing when said nut tightens the clamp foot in the blade groove.

55. 2. A hook rule attachment for the blade of an adjustable square or like device having an engageable clamping groove between its longitudinal edges, said attachment including an oblong block having a longitudinal blade bearing and beveled on its outer end face at the channel line of its blade bearing, said block having a vertical clamp receiving aperture through its top, the inner face of said blade bearing being vertically grooved in axial alinement with said aperture, 60 a threaded clamp screw in said aperture having a flattened portion extending into said vertical groove and having a foot at its lower end adapted to enter the blade groove, a nut on the screw for tightening the clamp foot in the groove of said 65 blade, a hook pin receiving aperture in said block adjacent an outer end thereof and extending through the longitudinal blade bearing, and a cylindrical hook pin of greater length than twice the vertical depth of said blade frictionally adjustable in said aperture, said hook pin being of

greater diameter than the thickness of the blade and being adjustably clamped against the end of the blade as said blade is clamped in its bearing when said nut tightens the clamp foot in said groove.

3. A hook rule attachment for the blade of an adjustable square or like device having an engageable clamping groove between its longitudinal edges, said attachment including a block channeled to provide a longitudinal blade bearing, said channel dividing the block into walls of unequal thickness, said block having a vertical clamp receiving aperture through its top over said channel, the inner face of the thicker wall being vertically grooved in axial alinement with said aperture, a 15 threaded clamp screw in said aperture and having a flattened portion extending into said vertical groove and having a foot at its lower end adapted to enter the blade groove, a nut on the screw for tightening the clamp foot in the blade groove, 20 a hook pin receiving aperture in said block adjacent an outer end thereof and extending through the longitudinal blade bearing channel, and a cylindrical hook pin of greater than twice the vertical depth of bearing, said pin being of 25 greater diameter than the thickness of the blade and being adjustably clamped against the end of the blade as said blade is clamped in its bearing when said nut tightens the clamp foot in said groove.

4. A hook rule attachment for the blade of an adjustable square or like device having an engageable clamping groove between its longitudinal edges, said attachment including a block channeled to provide a longitudinal blade bearing, 35 said channel dividing the block into walls of unequal thickness, said block having a vertical clamp receiving aperture through its top the inner face of said blade bearing being vertically grooved in axial alinement with said aperture, a threaded clamp screw in said aperture having a flattened portion extending into said vertical groove and having a clamp foot adapted to enter said blade groove, a nut on the screw for tightening the clamp foot in the blade groove, a hook pin receiving aperture in said block adjacent an outer end thereof and extending through the longitudinal blade bearing channel and symmetrically of the plane of said block and forming unsymmetrical grooves at the opposite inner faces of the bearing 40 channel walls, and a cylindrical hook pin of greater than twice the vertical depth of bearing, said pin being adjustably clamped against the end of the blade as said blade is clamped in its bearing when said nut tightens the clamp foot in said 45 groove.

5. A hook rule attachment for the blade of an adjustable square or like device having an engageable clamping groove between its longitudinal edges, said attachment including a block channeled to provide a longitudinal blade bearing, said block having a vertical clamp receiving aperture through its top, the inner face of said blade bearing being vertically grooved in axial alinement with said aperture, a threaded clamp screw 60 in said aperture having a flattened portion extending into said vertical groove and having a clamp foot adapted to enter said blade groove, a nut on the screw for tightening the clamp foot in the blade groove, a hook pin receiving aperture in 65 said block adjacent an outer end thereof and extending through the longitudinal blade bearing channel, and a cylindrical hook pin of greater than twice the vertical depth of bearing and of a diameter greater than the width of the blade 70

bearing, said hook pin being of greater diameter than the thickness of the blade and being adjustably clamped against the end of the blade as said blade is clamped in its bearing when said nut tightens the clamp foot in said groove.

6. A hook rule attachment for the blade of an adjustable square or like device having an engageable clamping groove between its longitudinal edges, said attachment including a block 5 channelled to provide a longitudinal blade bearing, said blade bearing dividing the block into walls of unequal thickness, said block having a vertical clamp receiving aperture through its top, the inner face of said blade bearing having a groove in the inner face of the thicker wall in axial alinement with said aperture, a threaded clamp screw in said aperture and having a flattened portion adjacent its lower end, a nut on the screw for tightening the clamp foot in the blade 10 groove, a hook pin receiving aperture in said block adjacent an outer end thereof and extending through the longitudinal blade bearing channel and forming unsymmetrical grooves at the opposite inner faces of the bearing walls, and a cylindrical hook pin of greater than twice the vertical depth of bearing, said pin being adjustably clamped against the end of the blade as said 15 blade is clamped in its bearing when said nut tightens the clamp foot in said groove.

7. A hook rule attachment for the blade of an adjustable square or like device having an engageable clamping groove between its longitudinal edges, said attachment including a block channelled to provide a longitudinal blade bearing, said 5 blade bearing dividing the block into walls of unequal thickness, said block having a vertical clamp receiving aperture through its top, the inner face of the thicker wall being grooved in axial alinement with said aperture, a threaded clamp screw in said aperture having a flattened portion extending into said vertical groove and having a clamp foot adapted to enter said blade groove, a nut on the screw for tightening the clamp foot in the blade groove, a hook pin receiving aperture in said block adjacent an outer end and extending through the longitudinal blade bearing and symmetrically of the plane of it and forming unsymmetrical grooves at the opposite 10 inner faces of the bearing channel walls, and a cylindrical hook pin of greater than twice the vertical depth of bearing, and of a diameter greater than the width of the blade bearing, said pin being adjustably clamped against the end of the blade, as said blade is clamped in its bearing 15 when said nut tightens the clamp foot in said groove. 20
